UNITED STATES PATENT OFFICE.

HARRY E. BOYD, OF AKRON, AND RUSSELL B. KOONTZ, OF SPRINGFIELD TOWNSHIP,
SUMMIT COUNTY, OHIO.

COLLAPSIBLE CORE.

1,093,105.

Specification of Letters Patent. Patented Apr. 14, 1914.

Application filed May 26, 1913. Serial No. 769,922.

To all whom it may concern:

Be it known that we, HARRY E. BOYD and RUSSELL B. KOONTZ, citizens of the United States, residing at Akron and Springfield Township, respectively, in the county of Summit and State of Ohio, have invented new and useful Improvements in Collapsible Cores, of which the following is a specification.

10 This invention relates generally to improvements in collapsible cores for manufacturing the outer shoes of double-tube pneumatic tires, and the object thereof is to provide a collapsible core which may be 15 quickly assembled or collapsed, the invention contemplating the provision of a plurality of segments, which, when united, will form an annular core-body for imparting to the interior of the tire-shoe during the manufacture thereof, the proper shape to receive the inner inflatable tube, the invention more particularly residing in the means whereby the various segments constituting the body portion of the core, are temporarily united. 20

25 More specifically, the invention resides in providing the abutting ends of the segment-shaped members with registering radially-extending notches so that when the ends of the segment-shaped members are 30 abutted radial openings are formed, portions of the openings being in each of the abutting ends. In order to unite the segment-shaped members of which the core is formed into an annular body there is secured 35 in the notches in the end of each segment a radially-extending member and also provided interengaging members in the cooperating ends of contiguous members, the members mounted on abutting segment-shaped members arranged to cooperate for 40 assisting in holding the segment-shaped sections in annular formation, the inner ends of a portion of the members projecting inwardly beyond the inner faces of the flanges forming portions of the core body. These 45 projecting ends are threaded to receive washer members having inclined faces and also to receive clamping nuts. The inner faces of the flanges surrounding the projecting inner ends of the members being pro-

vided with shallow grooves having inclined walls coöperating with the inclined walls of the washer members so that when the nuts are drawn up the inclined walls of the washer members will engage the inclined walls of the concentric grooves and force the abutting ends of contiguous segment-shaped sections into snug engagement with each other.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations and modifications can be resorted to which come within the scope of the claims hereunto appended.

In the drawings in which similar reference numerals indicate like parts in the different figures, Figure 1, is a plan view of a ring core embodying this invention; Fig. 2, is a longitudinal central sectional view of the abutting ends of two segment-shaped members showing the means employed for uniting them in annular formation; and Fig. 3, is a plan view of the elements shown in Fig. 2.

The ring core is constructed of a plurality of segment-shaped members which when united together, as hereinafter described, constitute an annulus the outer face of which is adapted to impart a desired configuration to the inner surface of the tire-shoe manufactured thereon. These segments are designated in the drawings by the reference numerals 1, 2, 3, and 4. These various segment-shaped members are preferably made hollow to reduce the weight of the finished core and the ends of each segment-shaped members are closed so as to present a smooth surface, and each of the sections is further provided with an inwardly-extending flange 5.

In order to simplify the description it may be stated that the temporary connecting means employed for uniting the various

segments together is common to all and hence, a description of one joint or coupling means employed for uniting two segment-shaped members together is deemed sufficient for a full understanding of the invention, and in order to illustrate this more fully, the description will be more particularly directed to the joint or coupling instrumentality employed between the segments 2 and 4.

The end of the segment-shaped member 2 is provided with a radially-extending notch or groove 6 in which is positioned a radial member 7 secured to the end of the member 2 through the medium of hold-fast devices 8. The outer portion 9 of this member 7 is arranged to extend longitudinally into a registering recess 12 formed in the member 4 and thereby constitute a key for preventing the transverse disarrangement of the sections with respect to each other. The head portion 9 is provided with an inclined inner face 11 for a purpose to be stated. Secured in the radial opening 12 in the end of 25 the member 4 which co-operates with the end of the member 2 is a radially-extending element 13 secured in position through the medium of hold-fast devices 14. The outer end of this element 13 is inclined to cooperate with the face 11 of the head 9 of the member 7. The inner end of the member 7 is cylindrical and threaded at 15 and projects inwardly beyond the inner faces of the flanges 9 of the members 2 and 4. Preferably concentric with the threaded portion 30 15 of the member 7 is an annular groove 16 the inner face 17 of which is inclined. Mounted on the threaded portion 15 of the member 7 is a cup-shaped washer member 18 the inner face 19 of which is inclined and arranged to engage the inclined face 17 of the registering grooves in 16 and the sections 2 and 4 and set up a wedging action when forced inwardly for drawing the ends 45 of contiguous segments toward each other into snug engagement. The washer member 18 is forced outwardly through the medium of a nut 20.

When the core is set up the various segment-shaped members 1, 2, 3 and 4 are arranged in annular formation with the ends thereof abutting and with the inclined outer faces of the members 13 interlocking against the inclined faces 11 of the members 7 which 50 prevent the outward movement of the ends of the segment-shaped sections. In order to lock the sections detachably in annular formation the cup-shaped washer members 18 are applied to the threaded portions 15 55 of the members 7 and are forced outwardly through the medium of nuts 20, in doing which the wedging action set up by the engagement of the inner face 19 of the washer 60 18 with the walls 17 of the sections tends to

force the ends of the sections together and 65 as the heads 9 of the members 7 extend longitudinally into the recesses 12 of the co-operating or coadjacent ends of the contiguous sections any lateral movement of the sections with respect to each other is prevented. 70 The core is dismounted after use by removing the nuts 20 on the members 7 which are positioned in the ends of the segment-shaped members 1 and 3 and after the washer members have been removed the segment-shaped 75 section 1 which constitutes a key member may be moved inwardly thereby permitting the removal of the other sections successively. The core is reassembled by reversing the foregoing operation. 80

We claim:

1. In a collapsible core for the manufacture of tire shoes, the combination of a series of segment-shaped sections adapted to be assembled into a circular core, the ends of the 85 sections abutting against each other and each formed with an inwardly-extending flange, the opposing ends of the sections being provided with registering radially-extending notches, radially-extending members mounted in each of said notches and fashioned to permit the members on the opposing ends of contiguous sections to interengage, one of the members on each section projecting radially and inwardly beyond the flange of 90 its section, the abutting flanges surrounding said projecting portion provided with annular grooves spaced from said notches having inclined faces, and washer members provided with inclined faces for co-operating 100 with inclined faces of said grooves applied to said projecting ends, and means for shifting said washer members to bring the inclined faces into co-operation for forcing the contiguous ends of sections together. 105

2. In a collapsible core for the manufacture of tire shoes, the combination of a series of segment-shaped sections adapted to be assembled into a circular core, the ends of the sections abutting against each other and each formed with an inwardly-extending flange, the opposing ends of the sections being provided with registering radially-extending notches arranged when said sections are abutted to form radial openings, 115 locking members mounted in the grooves at one end of each section and arranged to project into the groove in a contiguous section, co-operating members in the grooves in the ends of the other sections adapted to interengage with said first members, a portion of said members extending inwardly and provided with threaded shanks, the inner faces of the flanges surrounding said threaded members provided with annular grooves 120 having inclined faces, washer members having inclined faces for engagement with the inclined faces of said grooves applied to said

threaded members, and nuts on said threaded members for shifting said washer members outwardly to bring the inclined faces of the washer members and grooves into engagement for forcing the ends of the sections into snug engagement.

In testimony whereof we have hereunto

set our hands in presence of two subscribing witnesses.
